The ornamental design for a sanitizing station, as shown and described.

DESCRIPTION

FIG. 1 is a perspective view of a first embodiment of a sanitizing station;

FIG. 2 is a perspective view of a second embodiment of a sanitizing station;

FIG. 3 is a front elevation view of the sanitizing station of FIG. 1;

FIG. 4 is a front elevation view of the sanitizing station of FIG. 2;

FIG. 5 is a side elevation view of the sanitizing station of FIGS. 1 and 2;

FIG. 6 is a top plan view of the sanitizing station of FIGS. 1 and 2;

FIG. 7 is a bottom plan view of the sanitizing station of FIGS. 1 and 2; and,

FIG. 8 is a rear elevation view of the sanitizing station of FIGS. 1 and 2.

The broken lines are included for the purpose of illustrating portions of the sanitizing station that form no part of the claimed design. The column portion of the sanitizing station shown in FIGS. 1-5 and 8 is shown broken away in order to indicate that a specific height of this portion forms no part of the claimed design.
